UNITED STATES PATENT OFFICE.

OLNEY NEWELL, OF DENVER, COLORADO.

STOCK-CAR.

SPECIFICATION forming part of Letters Patent No. 375,562, dated December 27, 1887.

Application filed November 4, 1887. Serial No. 254,310. (No model.)

To all whom it may concern:

Be it known that I, OLNEY NEWELL, of Denver, in the county of Arapahoe and State of Colorado, have invented a new and useful Improvement in Stock-Cars; and I do hereby declare that the following is a full, clear, and exact description of the same.

The object of the invention is to generally improve the car as patented to me on the 19th 10 of July, 1887, No. 266,975, and particularly to provide means by which the water-trough may be opened positively by power applied to each end of the trough by one operation, and, secondly, to provide a movable partition which 15 will divide the car into apartments and separate the cattle during transportation, so as to preserve them from injury, which often results from the sudden stopping and starting of the cars. These partitions, when the car is to 20 be returned, may be supported close to the ceiling of the car out of the way, thus enabling the car to be used on its return for other kinds of freight.

The invention consists in the devices and 25 combination of devices hereinafter fully set forth.

In the drawings, Figure 1 represents a transverse sectional view of the car embodying my improved collapsible trough and the devices 30 for opening the same. Fig. 2 is a longitudinal section of the same.

As in the patent referred to, the water-trough consists of canvas or other flexible material adapted to be collapsed, with a strengthening-strip, G, protecting the inner side, to which it is connected, the opposite edge being supported against the side of the car. The strip G is supported by folding arms hinged to the side of the car beneath the trough, as shown 35 at a'. At each end of the trough I provide curved metallic arms D, one end of which is pivoted to the end of a bracket, b', projecting from the strengthening-strip G. The opposite end of the arm D is pivoted in the fork of a 40 sliding rod, B, which extends downwardly in suitable guides close to the wall of the car. The connection is the same at each end. A cable or chain extends from each of the rods B over pulleys E F to a lever, H. This lever 45 projects through the top of the car and is provided with an ordinary hand-wheel. By turn-

ing this operating-lever the cables are wound upon the end thereof, thus lifting the bars B at each end uniformly, and the upward movement of the bars will lift the inner ends of the 55 arms D secured thereto, and this movement will force the opposite ends of the arms connected to the strengthening-strip outward until the trough is opened and ready to receive the water. A ratchet-wheel holds the lever 60 at any desired point. When it is desired to collapse the trough again, the lever H is released by turning off the ratchet, and the bars B are forced to their former position by means of coiled springs B bearing against their upper ends. The coiled springs will not entirely 65 close the trough, so I provide a chain, c', extending to the outside of the car, connected with the strip G, so that the trough may be drawn closely against the side of the car. 70

As indicated heretofore, it has been found desirable to separate stock-cars by partitions, as the sudden stopping or starting of the cars creates a surge which throws the cattle one against the other and against the ends of the 75 cars, which result in bruising, seriously maiming, and often killing the stock. It is also desirable that these partitions shall be made so as to be stowed away in the least possible space when the car is to be returned with other 80 freight.

I extend across the car near the roof an iron rod, a, solid or tubular, with screw-nuts upon the outer ends to clamp it tightly in place, and from this rod I suspend a partition or grate, 85 I, which may be made of wooden bars and metallic rods, or in any other suitable manner, so as to separate the cattle without taking up too much room or interfering with the light or ventilation. The partition is suspended from 90 the rod a by hangers B' B', which are provided with suitable eyes through which the rod passes. The gate or partition is held in place by sliding bolts f f near the center of the partition, and may be projected beyond or through 95 the opening in the side of the car to hold the partition steadily in place. A drum or grooved wheel or pulley is provided on the top of the car in a convenient position provided with a crank and having a small wire 100 cable terminating in a hook wound thereupon.

When the car has reached its destination and

the cattle have been removed, and it is desired to pack the car with other freight on its return-trip, the partition is elevated to the top of the car by means of the drum and its chain, 5 the hook of the said chain being caught in the hook *d* on the lower end of the partition, and in this way the partition is hoisted to the top of the car, where it may be held by the chains *d'*, or in any other suitable manner.

10 I claim as my invention—

1. In a stock-car, a collapsible water-trough, arms *B* at each end, pivotally connected to the free side of said trough and extending to the car-side, and an intermediate device connected to 15 the free end of the arm for operating the said arms positively, substantially as described.

2. In a stock-car, the combination of a collapsible trough, the arms *D*, connected to the free side of said trough, sliding bars *B*, connected to the other ends of the arms, and means 20 for operating said bars, substantially as described.

3. In a stock-car, in combination, a collapsible trough, arms *D*, connected to the free

side of the trough, means for operating said 25 arms to open the trough, and means for closing the same, substantially as described.

4. In a stock-car, the combination of the water-trough, the arms *D* at each end thereof, the sliding bars *B*, connected to the arms, the 30 cables between the bars *B* and the operating-lever, and the spring *E*, for returning the bars, substantially as described.

5. In a stock-car, the collapsible water-trough, curved arms *D*, pivotally connected to 35 the inner sides of said trough, sliding bars *B*, also having a pivotal connection with the arms, the cables connecting said bars with the operating-lever, and the spring *E*, for returning said bars *B*, substantially as described. 40

In testimony whereof I have signed my name to this specification in the presence of two subscribing witnesses.

OLNEY NEWELL.
